UNITED STATES PATENT OFFICE.

THEODORE M. RICHARDSON, OF STOCKTON, MAINE, ASSIGNOR OF THREE-FOURTHS TO JAMES M. RUSSELL, OF BOSTON, MASSACHUSETTS.

THILL-CO尤LING.

SPECIFICATION forming part of Letters Patent No. 267,937, dated November 21, 1882.

Application filed September 9, 1882. (No model.)

To all whom it may concern:

Be it known that I, T. M. RICHARDSON, a citizen of the United States, and a resident of Stockton, in the county of Waldo and State of Maine, have invented a new and valuable Improvement in Thill-Couplings; and I do hereby declare that the following is a full, clear, and exact description of the construction and operation of the same, reference being had to the annexed drawings, making a part of this specification, and to the letters and figures of reference marked thereon.

Figure 1 of the drawings is a vertical sectional view of my coupling, and Fig. 2 is a plan view of the same.

This invention has relation to thill and pole couplings; and it consists in the construction and novel arrangement of the spring rubber holder and rubber cushion, and of the lever-nut and rubber washer on opposite ends of the coupling-bolt, all as hereinafter set forth.

In the accompanying drawings, the letter *a* designates the axle-clip, carrying the shackle-body *b*, having the lateral perforated arms *c*, between which is an interspace designed to receive the cylinder-shaped head *d* of the shaft-iron *e*. This head *d* is transversely perforated to receive the coupling-bolt *g*, the ends of which extend through the perforations in the arms *c*. Between the head *h* of this bolt and the adjacent arm of the shackle is placed a rubber washer, *k*. On the threaded end of the bolt, outside of the opposite arm of the shackle, is arranged a lever-nut, *l*, said nut having an arm formed with an end stop or bearing, *m*, which is designed, when the nut is turned home, to engage a catch or projection on the side of the shackle or shackle-arm. When in engagement therewith the lever-nut is held firmly in position by the elastic action of the rubber washer under the head of the bolt. Under the shaft-iron is connected to the shaft a spring-holder, *s*, which is slotted longitudinally at *n* for the passage of the fastening-bolt *p*, and is provided with a concave curved rear end portion, *t*, extending around under the cylinder-head *d* and upward behind the same, finally terminating in a horizontal flange or holding-spurs, as indicated at *q*. This rear portion, *t*,

of the spring-arm forms a holder for the rubber cushion *r*, which is located in the concavity behind the coupling-bolt, its upper portion or top being engaged by the holding-projection *q*. The rubber cushion is by this spring-arm held firmly, but in an elastic manner, against the rear of the cylinder-head of the shaft-iron. The slotted arm of the spring-holder provides means whereby the rubber cushion can be drawn more closely against the cylinder-head, when this becomes necessary in consequence of the wearing away of the rubber cushion by the constant vibrations of the shaft. It is designed by holding the bolt and cylinder-head in the manner hereinbefore described to avoid looseness and rattling.

A packing of rubber or the like has been interposed between the head of the bolt and the thill-eye, and a lock-nut has been used at the point of the bolt in this connection; but a construction of this character is not broadly claimed herein.

Having described this invention, what I claim, and desire to secure by Letters Patent, is—

1. A thill or pole coupling having the adjustable spring rubber holder *s*, attached to the shaft, and extending around up behind the cylinder-head to receive the rubber cushion, which engages said head, substantially as specified.

2. A thill or pole coupling having the adjustable spring rubber holder *s*, attached to the shaft, and curved upward at its rear end, finally terminating in a horizontal flange or spur projection, *q*, substantially as specified.

3. A thill or pole coupling having the rubber washer *k* under the head of the coupling-bolt *g*, the lever-nut *l* on the end of the same, formed with an end stop or bearing, *m*, and a catch or projection on the shackle or shackle-arm, substantially as specified.

In testimony that I claim the above I have hereunto subscribed my name in the presence of two witnesses.

THEODORE MANSFIELD RICHARDSON.
